US0D1017601S

(12) **United States Design Patent** (10) **Patent No.:** **US D1,017,601 S**
(45) **Date of Patent:** **** Mar. 12, 2024**

(54) **COMPUTER STORAGE DEVICE**

(71) Applicant: **HANWHA TECHWIN CO., LTD.**,
Seongnam-si (KR)

(72) Inventors: **Ho Jin Park**, Seongnam-si (KR); **Mun Jun Park**, Seongnam-si (KR)

(73) Assignee: **HANWHA VISION CO., LTD.**,
Seongnam-si (KR)

(**) Term: **15 Years**

(21) Appl. No.: **29/798,901**

(22) Filed: **Jul. 12, 2021**

(30) **Foreign Application Priority Data**

Jan. 11, 2021 (KR) 30-2021-0001284

(57) **CLAIM**

The ornamental design for a computer storage device, as shown and described.

DESCRIPTION

FIG. 1 is a front perspective view of a computer storage device showing a new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is an exploded perspective view thereof.

Broken lines seen in the drawings depict portions of the computer storage device that form no part of the claimed design.

1 Claim, 8 Drawing Sheets
